UNITED STATES PATENT OFFICE.

JOHN TARANTO, OF WALTHAM, MASSACHUSETTS, ASSIGNOR TO DRAPER CORPORATION, OF HOPEDALE, MASSACHUSETTS, A CORPORATION OF MAINE.

NEEDLE-FEELING MECHANISM FOR LOOMS.

Application filed January 13, 1923. Serial No. 612,443.

To all whom it may concern:

Be it known that I, JOHN TARANTO, a citizen of the United States, and a resident of Waltham, county of Middlesex, State of Massachusetts, have invented an Improvement in Needle-Feeling Mechanism for Looms, of which the following description, in connection with the accompanying drawing, is a specification, like characters on the drawing representing like parts.

This invention relates to improvements in feeler mechanism for looms having a reciprocating or vibrating actuator adapted when restrained to effect a change in the operation of the loom.

More specifically the invention relates to improvements upon the general type of feeler illustrated in my prior Patent No. 1,369,990, granted March 1, 1921, and in the 20 patents to E. H. Ryon No. 933,492, granted September 7, 1909, No. 972,722, granted October 11, 1910, and No. 989,429, granted April 11, 1911.

The object of the present invention is to 25 provide feelers of the general type disclosed in the patents aforesaid with a mechanism having a needle adapted to penetrate the filling upon the filling carrier upon the beat-up of the lay until substantial exhaustion is 30 reached, whereupon the needle mechanism is moved relatively to the feeling end of the feeler and caused to actuate suitable mechanism which will restrain the reciprocating or vibrating movement of the actuator and 35 thereby effect a change in the operation of the loom. By providing a needle feeler of this character practically all of the filling can be wound off of the filling carrier before transfer is effected.

40 A further object of the invention is to provide a needle feeler of the character described having a needle support mounted upon the feeler in such a manner that it can be readily assembled upon or removed from the feeler.

A further object of the invention is to 45 provide a needle support of the character described from which the needle can be readily removed.

50 A further object of the invention is to provide a feeler of the character described with a pivotally mounted laterally swinging lever having an arm normally extending in the direction of movement of the 55 feeler in operative relation to the actuator-

restraining mechanism and controlled by the relative movement of the needle support and feeler when caused by engagement of the needle with the filling carrier upon substantial exhaustion of the filling to effect a 60 change in the operation of the loom.

These and other objects and features of the invention will more fully appear from the following description and the accompanying drawing and will be pointed out in 65 the claims.

In the drawings:

Fig. 1 is a side elevation of a feeler mechanism embodying the invention, the frame upon which it is supported being 70 broken away;

Fig. 2 is a plan view of the same, the reciprocating or vibrating actuator for initiating a change in the operation of the loom being shown in dotted lines; 75

Fig. 3 is an end elevation of the feeler mechanism shown in Fig. 1;

Fig. 4 is an enlarged plan view of the end portion of the feeler, showing the needle support removably mounted therein and provided with a detachable needle extending through the feeling end of the feeler; and, 80

Fig. 5 is a vertical sectional view on line 5—5 Fig. 4 illustrating the form of the co-operating guide and guideways of the feeler 85 and the needle support.

The feeler mechanism which is illustrated in the drawing comprises the usual bracket 1 which is adapted to be mounted upon the end of the loom frame and is provided with 90 upwardly extending branches 2 and 3, the branch 3 having an upward extension 4 provided with a vertical slot 5 forming a guideway for the reciprocating or vibrating actuator 6, such as is illustrated in the 95 aforesaid patents, and which operates when restrained to effect a change in the operation of the loom. The extension 4 of the branch 3 is provided with a transverse aperture 7 which forms a guideway for an actuator-engaging member, preferably in the form of a rod 8, the end of which may be reciprocated across the path of the actuator in such a manner as to restrain the movement thereof and effect a change in the operation of 100 the loom.

The actuator-engaging rod is pivotally connected at its opposite end to the upper bifurcated end of an arm 9 of a rock shaft 10 which is pivotally mounted in bosses 11 110

2
and 12 extending laterally in the arms 2 and 3 of the bracket 1. A helical spring 13, which surrounds the rock shaft 10 and is anchored at one end to the boss 12 and at its 5 opposite end to a collar 14 adjustably secured to the rock shaft by a screw 15, serves normally to rotate the rock shaft 10 in a clock-wise direction and to force the end of the actuator-restraining member 8 across the 10 slot 5 so that reciprocating movement of the actuator 6 is prevented and the initiation of a change in the operation of the loom effected in a manner more fully described in the 15 patents above mentioned. The rock shaft 10 has at its opposite end an upwardly extending arm 16 to which is attached a lateral extension 17 which normally lies in the path 20 of the end of an arm of a lever which is pivotally mounted upon the feeler and is reciprocated with the feeler upon each beat-up of the lay as the filling upon the filling carrier engages the end of the feeler, but is 25 swung out of engagement with the extension 17 upon detection of filling, thus permitting the spring 13 to hold the actuator-restraining member in the path of the actuator and thereby initiate a change in the operation of the loom. The normal position of the arm 16 relatively to the end of the arm 33 of the 30 lever upon the feeler is adjustably limited by a set screw 17* extending through the arm 16 and abutting at its end against the end of the stand 20. The arm 16 with its extension 17, the rock shaft which is normally under 35 the influence of the spring 13, the arm 9 and the rod 8, therefore, constitute spring-operated actuator-restraining mechanism operable to initiate a change in the operation of the loom which is controlled by feeler 40 mechanism embodying the present invention in a manner hereinafter described.

The feeler comprises a sliding bar 18 the feeling end 19 of which is adapted to enter the shuttle and to feel upon the filling on the 45 filling carrier in the shuttle. The feeler slide is mounted in suitable ways in a stand 20 which is provided with a depending boss or extension 21 having a slot 22 leading to a threaded aperture which engages a screw 50 threaded stud 23 carried by a bolt 24 extending through the arm 2 of the bracket 1. The screw threaded stud 23 is clamped in position by a nut 25 on the bolt 24. The boss 21 is 55 adjustably secured upon the screw threaded stud 23 by a set screw 26 which passes through the bifurcated portion of the boss and across the slot 22.

The stand 20 is provided with a cap 27 having closed ends in which a rod 28 is 60 mounted, said rod having an enlarged screw threaded end 29 engaging complementary threads in one end of the cap and provided with a smaller stem extending through the other end of the cap. The rod 28 extends beyond the end of the stem and is provided

with a slot to receive a screw driver by means of which the stem may be adjusted. The rod 28 may be secured in adjusted position by a suitable set screw 30 passing downwardly through the top of the casing into engagement with the rod 29. 70

The feeler slide 18 is provided with an upwardly extending boss 31 through which the rod 28 extends and a helical spring 32, abutting at one end against the boss 31 and at its 75 opposite end against the end wall of the casing, tends normally to force the feeler to extended or feeling position. The extension of the feeler is limited by the engagement of the boss 31 with a shoulder upon the rod 28 80 formed by the junction of the main portion of the rod 28 with the enlarged end portion 29. The extreme feeling position of the feeler may be adjusted by rotating the rod 28 to position the shoulder against which the 85 boss on the feeler plate engages at a greater or less distance from the end of the cap 27.

The means for controlling the actuator-restraining mechanism comprises a lever, preferably in the form of a bell crank lever 90 having one arm 33 extending substantially in parallelism with the direction of movement of the feeler slide and an arm 34 extending preferably at right angles thereto, said lever being pivotally mounted upon a 95 stud 35 extending upwardly from the feeler. A screw 36, having a head 37, is adjustably seated in the arm 34 of the bell crank lever and is adapted to be clamped in adjusted position by a nut 38. 100

In previous constructions, such as disclosed in my prior Patent No. 1,369,990, the head 37 of the screw was adapted to engage the wall of the shuttle upon substantial exhaustion of filling and by rocking the bell 105 crank lever modified the normal operation of the actuator-restraining mechanism to effect a change in the operation of the loom.

In the present invention the bell crank lever is controlled by a needle feeling mechanism which is more sensitive than the feeling mechanism of prior constructions of this character and is adapted to permit a greater amount of filling to be wound off of the filling carrier before transfer is called 115 for than in previous constructions.

In the preferred embodiment of the invention illustrated herein a needle 39 extends through a suitable aperture in the feeling end 19 of the feeler and is provided 120 with a preferably vertical wedge-shaped end adapted to penetrate the filling upon the filling carrier. The needle 39 is detachably secured at its opposite end in a needle support 40 by a pin 41 which passes downwardly through the needle support and the needle and which may be removed by a suitable tool. In order to enable the needle to be readily removed the needle support is provided with an aperture 42 into which the 125 130

- end of the needle 39 extends, but does not cross so that a wedge-shaped tool forced into the aperture 42 will displace the needle and enable it readily to be withdrawn.
- 5 The base portion of the needle support 40 desirably is of substantially the same thickness as the feeler 18 and is provided with guideways 43 which engage complementary guides 44 upon the walls of a slot 45 in the 10 end portion of the feeler. This slot in the feeler desirably is closed at its ends and is conveniently formed by boring holes through the feeler at suitable distances apart and milling away the stock between the holes 15 to provide the slot 45 and also to form the guides 44 in the walls of the slot. In order to permit the needle support to be assembled upon and removed from the feeler, the guides 44 terminate at a sufficient distance 20 from one end of the slot to permit the base of the support to be introduced into the slot and then moved lengthwise of the slot to cause the guideways of the support to engage the guides upon the feeler.
- 25 The feeler support is provided with an upwardly extending, preferably integral, standard 46 having a lateral extension 47 which is positioned to engage the head 37 of the screw which is adjustably mounted in 30 the arm 34 of the bell crank lever. A spring 48, connected at one end to the stud 35 upon which the bell crank lever is mounted, and at its other end to a lug 49 extending downwardly from the needle support 40, serves 35 to maintain the extension 47 of the standard of the needle support constantly in engagement with the head 37 of the screw upon the bell crank lever.
- Resilient means, such as a spring 50, connected to the feeler and to the arm 33 of the bell crank lever which is mounted upon the feeler, serves normally to maintain the arm 33 of the feeler in substantial parallelism with the direction of movement of the feeler 40 so that the end of the arm 33 is normally in the position to engage the lateral extension 17 of the arm 16 of the rock shaft 10 and upon reciprocation of the feeler oscillates 45 the rock shaft against the action of the spring 13 and removes the actuator-restraining member 8 from the path of the reciprocating or vibrating actuator 6, so that no 50 change in the operation of the loom will be effected by the normal reciprocation of the feeler.
- In the operation of the device the feeling end 19 of the feeler is engaged by the filling upon the filling carrier in the shuttle upon 55 each beat-up of the lay and so long as there is a sufficient amount of filling upon the filling carrier the wedge-shaped end of the needle 39 will penetrate the filling without causing any relative movement between the needle support and the feeler. The feeler, therefore, will be carried back bodily and 60 the end of the arm 33 of the bell crank lever will be caused to engage the extension 17 of the arm 16 of the rock shaft 10 and remove the rod 8 from the path of the actuator. When, however, the filling upon the filling 65 carrier is substantially exhausted the penetrating end of the needle 39 will engage the filling carrier itself and will be forced backwardly thereby, thus moving the needle carrier support and causing the extension 47 of the standard 46 of the needle carrier to press upon the head 37 of the screw in the arm 34 of the bell crank lever thereby rocking said bell crank lever laterally about its pivot and swinging the end of said lever out of operative relation to the extension 17 of the arm 16 of the rock shaft 10, so that when the feeler is reciprocated by its engagement with the filling carrier the rock shaft 10 will not be rotated and the actuator-restraining member 8 will remain in the path of the actuator 6 thereby restraining its movement and initiating a change in the operation of the loom.
- By reason of the fact that a slight relative movement between the needle support and the feeler serves to actuate the bell crank lever, transfer will not be called for until a very small amount of filling remains upon the filling carrier, thus producing a considerable saving in filling and enabling the bobbin to be more easily stripped of whatever filling remains upon it.
- By reason of the easy removal and replacement of the needle and needle support the 100 feeling mechanism can be readily maintained in a condition of maximum efficiency.
- While the feeling mechanism is illustrated in the accompanying drawings as normally acting to reciprocate the actuator-restraining mechanism, substantially the same mechanism can be readily applied to the construction illustrated in my prior Patent No. 1,369,990 in which the actuator-restraining mechanism is normally withheld from operative position and is actuated only upon detection by the feeler of substantial exhaustion of filling upon the filling carrier.
- It will be understood that the embodiment of the invention disclosed herein is of an 110 illustrative character and is not restrictive and that various changes in form, construction and arrangement of parts may be made within the spirit and scope of the claims.
- Having thus described my invention, what I claim as new, and desire to secure by Letters Patent, is:
1. Feeler mechanism for looms comprising a yieldable feeler to engage the filling upon the filling carrier in the shuttle upon the beat-up of the lay, a needle support mounted on said feeler having a needle normally projecting beyond the filling engaging end of the feeler to penetrate the filling on the filling carrier, a bell crank lever pivotally 125
- 120 130

mounted upon said feeler having one arm extending longitudinally of said feeler, resilient means acting upon said needle support to cause constant engagement thereof with the other arm of said bell crank lever, whereby relative movement between the needle support and feeler, caused by the engagement of said needle with the filling carrier upon substantial exhaustion of filling, will swing said lever laterally without lost motion and means controlled by the movement of said lever to effect a change in the operation of the loom.

2. Feeler mechanism for looms comprising a yieldable feeler to engage the filling upon the filling carrier in the shuttle upon the beat-up of the lay, a needle support slidably mounted in ways in said feeler having a needle normally projecting beyond the filling-engaging end of said feeler to penetrate the filling on the filling carrier, a bell crank lever pivotally mounted on said feeler to swing laterally in a horizontal plane and having an arm normally extending in the direction of reciprocation of said feeler and another arm extending in angular relation thereto having an adjusting screw engaging said needle support, resilient means acting upon said needle support to cause constant engagement of said needle support with said adjusting screw whereby the adjustment of said screw will effectively determine the distance said needle projects beyond the end of said feeler and relative movement between said needle support and feeler, caused by engagement of the needle with the filling on the filling carrier upon substantial exhaustion of filling, will swing said lever laterally without lost motion and means controlled by the lateral swinging movement of said lever to effect a change in the operation of the loom.

3. Feeler mechanism for looms comprising a yieldable feeler to engage the filling upon the filling carrier in the shuttle upon the beat-up of the lay, a needle support removably mounted in ways in said feeler, a needle detachably secured to said needle support and extending through the filling-engaging end of said feeler and mechanism operable by relative movement between said needle support and feeler caused by the engagement of said needle with said filling carrier upon substantial exhaustion of filling to effect a change in the operation of the loom.

4. Feeler mechanism for looms comprising a yieldable feeler having a recess therethrough adjacent its feeling end provided with parallel walls having guides extending in the direction of the line of movement of said feeler, a needle support slidably mounted in said recess having ways complementary to said guides, a needle carried by said needle support extending through the feel-

ing end of said feeler to penetrate the filling on the filling carrier and means operable by relative movement between said needle support and feeler caused by the engagement of the needle with the filling carrier to effect a change in the operation of the loom.

5. Feeler mechanism for looms comprising a yieldable feeler having a recess therethrough adjacent its feeling end provided with parallel walls having guides extending in the direction of the line of movement of said feeler and terminating at a distance from one end of said recess, a needle support slidably mounted in said recess having ways complementary to the guides in the walls of said recess, but of such length as to permit the introduction and removal of the needle-supporting ways between the end of the guides and the end of the recess, a needle carried by said needle support extending through the feeling end of said feeler to penetrate the filling upon the filling carrier and means operable by relative movement between said needle support and feeler, caused by the engagement of the needle with the filling carrier, to effect a change in the operation of the loom.

6. Feeler mechanism for looms, having a reciprocating actuator operating when restrained to initiate the action of means for effecting a change in the operation of the loom, comprising a spring-operated actuator-restraining mechanism having means tending normally to engage and arrest said actuator, a yieldable feeler having a feeling end to engage the filling on the filling carrier upon the beat-up of the lay, a laterally swinging lever pivotally mounted on said feeler, resilient means normally acting to hold one arm of said lever in substantial parallelism with the direction of movement of said feeler and normally acting upon reciprocation of said feeler to withdraw said restraining member from engaging relation to said actuator, a needle support slidably mounted on said feeler having a needle projecting beyond the feeling end of said feeler to penetrate the filling on the filling carrier and provided with means to engage and swing said lever laterally upon relative movement between said needle support and feeler upon engagement of the needle with the filling carrier, thereby acting to remove said lever from operative relation to said actuator-restraining mechanism, whereby the actuator will be restrained and a change in the operation of the loom effected.

7. Feeler mechanism for looms, having a reciprocating actuator adapted when restrained to initiate the action of means for effecting a change in the operation of the loom, comprising a feeler stand, a rock shaft mounted therein having an arm connected to an actuator-restraining member

reciprocable across the path of the actuator, resilient means normally tending to hold said actuator-restraining member in the path of the actuator, a feeler yieldably 5 mounted in said stand, to engage the filling upon the filling carrier in the shuttle upon the beat-up of the lay, a needle support reciprocably mounted in said feeler having a needle normally projecting beyond the filling-engaging end of said feeler to penetrate the filling on the filling carrier, a laterally movable lever pivotally mounted on said feeler having an arm normally extending substantially in parallelism with said feeler 10 and extending beyond the end thereof, an arm on said rock shaft located in the path of the end of said lever and operated upon 15

reciprocation of said feeler to withdraw said actuator-restraining member from the path of said actuator, means on said lever engaging said needle support acting upon relative movement between said needle support and feeler, caused by engagement of said needle with the filling carrier, to swing said lever laterally and remove the end thereof 20 from engaging relation with said rock shaft arm, whereby upon detection of substantial exhaustion of filling said actuator-restraining member will be permitted to remain in the path of the actuator and thereby effect 25 a change in the operation of the loom.

In testimony whereof, I have signed my name to this specification.

JOHN TARANTO.
